Primary Examiner—Theodore M. Shooman
Assistant Examiner—R. Barkai[57] **CLAIM**

The ornamental design for a clip-on sunglasses with holographic lens, as shown and described.

DESCRIPTION

FIG. 1 is front elevational view of a clip-on sunglasses with holographic lens showing my new design;
FIG. 2 is a rear elevational view thereof;
FIG. 3 is a top perspective view thereof;
FIG. 4 is a bottom plan view thereof;
FIG. 5 is a right side elevational view thereof; and,
FIG. 6 is a left side elevational view thereof.

The fragmentary cube depicted by means of broken lines in the figures has been shown for illustrative purposes only and forms no part of the claimed design.
